[57] CLAIM

The ornamental design for an automobile tire, as shown and
described.

DESCRIPTION

FIG. 1 is a front perspective view of an automobile tire
showing our new design, it being understood that the tread
design is repeated uniformly throughout the circumference
of the tire and the opposite side is the same as that shown;
FIG. 2 is a front elevational view thereof;
FIG. 3 is a right side view thereof; and,
FIG. 4 is an enlarged fragmentary front elevational view
thereof.
